UNITED STATES PATENT OFFICE.

HENRY WEISS, OF MILLBRAE, CALIFORNIA.

DESIGN FOR A WATER COOLER.

Application filed March 8, 1926. Serial No. 16,820. Term of patent 3½ years.

To all whom it may concern:

Be it known that I, HENRY WEISS, a citizen of the United States of America, residing at Millbrae, in the county of San Mateo and State of California, have invented a new, original, and ornamental Design for a Water Cooler, of which the following is a specification, reference being had to the accompanying drawing, forming a part thereof.

The figure is a front elevation of a water cooler showing my new design.

I claim:

The ornamental design for a water cooler, substantially as shown.

HENRY WEISS.
